(57) **CLAIM**

The ornamental design for a locking head of a pipe clamp, as shown and described.

DESCRIPTION

FIG. 1 is a perspective view of a locking head of a pipe clamp in accordance with the design;

FIG. 2 is a left side view of the locking head of a pipe clamp of FIG. 1;

FIG. 3 is a right side view of the locking head of a pipe clamp of FIG. 1;

FIG. 4 is a rear view of the locking head of a pipe clamp of FIG. 1;

FIG. 5 is a front view of the locking head of a pipe clamp of FIG. 1;

FIG. 6 is a top plan view of the locking head of a pipe clamp of FIG. 1;

FIG. 7 is a bottom view of the locking head of a pipe clamp of FIG. 1;

FIG. 8 is a perspective view of a locking head of a pipe clamp of FIG. 1 in gray scale;

FIG. 9 is a left side view of the locking head of a pipe clamp of FIG. 8;

FIG. 10 is a right side view of the locking head of a pipe clamp of FIG. 8;

FIG. 11 is a rear side view of the locking head of a pipe clamp of FIG. 8;

FIG. 12 is a front side view of the locking head of a pipe clamp of FIG. 8;

FIG. 13 is a top plan view of the locking head of a pipe clamp of FIG. 8; and,

FIG. 14 is a bottom view of the locking head of a pipe clamp of FIG. 8.

The broken lines in the drawings form no part of the claimed design.

1 Claim, 14 Drawing Sheets
